8 Claims. (Cl. 250—27)

1

In various types of apparatus for accelerating charged particles such as electrons to high velocity and hence high electron voltages, and in which the electrons travel in substantially a circular orbit, it has been found especially difficult with apparatus so far developed to introduce the electrons into and remove them from the orbit, and to compel them to strike under satisfactory conditions an anti-cathode or anode. These difficulties all arise from the fact that the additional forces, employed to modify those forces under which the stream of electrons is made to follow the orbit while accelerating them continuously along the orbit, require for their production an extremely long time in comparison with the time required by the electrons to make one trip around the orbit, the latter being of the order of 1×10^{-8} second. Because of this the electron paths vary slowly, as if the electrons could follow the additional, deflecting forces without inertia, i. e. gradually and continuously and in general without impressed free oscillations. Under these conditions it has thus been found very difficult to produce such additional forces as will cause the accelerated electrons to leave the orbit in a narrowly confined beam along a prescribed path necessary for the electrons to strike the anode or leave the tube in which acceleration takes place, or alternatively to guide the electrons along a prescribed path from an electron emissive source into the circular orbit at the beginning of the acceleration phase.

For example, in the "betatron" type which is also commonly known as a "magnetic induction accelerator" or "ray transformer," wherein the electrons are accelerated round and round the orbit under the combined actions of an induction magnetic field and a guiding magnetic field, one method already proposed for causing the accelerated stream of electrons to be diverted from the orbit is by superimposing an auxiliary magnetic field on the main magnetic guiding field. This has the effect of altering the ratio between the induction and guiding field components with the result that the path of the electron stream expands. The electron stream after attaining the outer boundary of the orbit where the stabilizing forces become zero then travel outwardly along a spiral path. Since, however, the orbit must be axial-symmetrical due to the circular motion, the electrons leave the tube uniformly along the entire circumference contrary to the result desired. Even if the orbit is altered at the outer boundary for a certain distance by the addition of auxiliary forces acting upon the elec-

2

trons, the change can never be made so suddenly that the electrons, which at the same time are usually also influenced by low order accidental disturbances, are not ejected from the tube at unintentional places.

The general object of this invention is to provide an improved arrangement for guiding the electron stream into or away from the orbit so that substantially the entire stream will follow a selected path. As will become more clear from a reading of the detailed description which follows, this objective is attained by subjecting the stream of electrons to a first deflecting force directed perpendicular to their direction of motion and which force is applied over at most one fourth of the circumference of the orbit and also to other deflecting forces applied over the orbit in a sense which is radially opposite to that of the first force.

While the principles of the invention are applicable to various types of electron accelerators and other devices where the electrons follow a circular path, it will be described in connection with its application to the betatron type of accelerator to illustrate several preferred forms of construction which are considered practical for attaining the desired result. In the drawings which show these various embodiments:

Fig. 1 is a view in central vertical section of 30 the improved construction in which the electron deflecting forces auxiliary to those forces which cause acceleration of the electrons are derived from electrostatic fields;

Fig. 2 is a horizontal section taken on line 35 2—2 of Fig. 1 showing only the tube and deflection plates, and drawn to a slightly larger scale;

Fig. 3 is a curve in development illustrating the electron path relative to the orbit when methods already known are employed to effect a 40 deflection of the electrons from the orbit at the end of the acceleration phase;

Fig. 4 is a view similar to Fig. 3 illustrating the deflection path of the electrons when the improved deflection methods according to the present invention are employed;

Fig. 5 is a horizontal section similar to Fig. 2 showing an arrangement wherein the electron deflecting forces are produced by electromagnetic fields;

Fig. 6 illustrates a modification of the arrangement shown in Fig. 5 employing magnetic fields located adjacent one another for setting up the mutually opposite deflecting forces;

Fig. 7 is a view similar to Fig. 4 showing the

deflection path of the electrons according to the Fig. 6 construction;

Fig. 8 shows a further modification of the arrangement illustrated in Fig. 5 wherein the magnetic fields producing the mutually opposed deflecting forces are positioned unsymmetrically;

Fig. 9 shows the type of electron deflection which obtains when the deflecting forces are arranged unsymmetrically as shown in Fig. 8;

Fig. 10 is a view on line 10-10 of Fig. 11 illustrating somewhat diagrammatically a modified arrangement wherein the components which produce the deflecting forces are inclined with respect to the plane of the electron orbit to produce deflecting forces which include a component of force perpendicular to the plane of the electron orbit;

Fig. 11 is a horizontal section similar to Fig. 2 illustrating use of one form of the present inventive concept for introducing a stream of electrons into the orbit at the beginning of the acceleration phase;

Fig. 12 is a view in development of the potential channel of the stabilizing forces acting upon the electrons illustrating another embodiment of the invention for introducing electrons into the orbit at the start of the acceleration phase;

Fig. 13 is a horizontal section illustrating an arrangement wherein the deflecting forces extend substantially around the entire circumference of the orbit, and

Fig. 14 is a development of the orbit showing the characteristic of the electron deflection which obtains when the Fig. 13 construction is utilized.

Referring now to Figs. 1 and 2, the betatron there illustrated is seen to be comprised of a magnetic field structure 10 made up from steel laminations of appropriate contour so as to provide a pair of mutually confronting cylindrical poles 11-11' separated by an air gap 12 and located concentrically along the axis of revolution $a-a$, and a pair of annular poles 13-13' also confronting one another and which are likewise arranged concentric to the axis $a-a$, and separated by air gap 14. Yoke members 15 complete the magnetic circuit for a cyclically varying magnetic flux set up in the annular and cylindrical poles. Poles 11-11' and 13-13' are surrounded by an annular winding preferably split into two coil sections 16-16' connected in series for energization from a source of alternating current of suitable frequency as for example 100 cycles-sec. applied to terminals 17.

An annular evacuated tube 18 rests in the air gap 14 between poles 13-13' and thereby surrounds the axial poles 11-11'. Located within the tube is an electron injector of a well known type such as indicated in Fig. 2 by reference number 20. In the construction illustrated, the injector 20 is located radially outward from the circular orbit k , and the electron stream after being accelerated is led out of the tube 18 through a tangentially arranged outlet 19.

By a control arrangement which is well known and for such reason has not been illustrated, the cathode of the injector 20 is energized periodically in timed relation with the cyclic magnetic field produced in the magnetic structure 10 by energization of winding 16-16' so as to produce a stream of electrons at just about the instant the magnetic field passes through the zero value. The electron stream circulating along the circular orbit k undergoes a constant acceleration under the influence of the magnetic field. The latter divides into essentially two operating com-

ponents. One of these, the "inducing field" component acting axially through poles 11-11' and indicated by lines ϕ_1 in Fig. 1 may be considered as being responsible for the acceleration of the electron stream; the other component commonly referred to as the "control field" and which is indicated in Fig. 1 by lines ϕ_c acts axially through the annular poles 13-13' to produce a centripetal effect upon the electron stream to offset the centrifugal forces of the electrons caused by their motion along the circular orbit k . Throughout the increasing acceleration of the electron stream, the centripetal force, which likewise increase, substantially matches the increasing centrifugal forces of the electrons with the result that the stream theoretically is confined to an orbit of constant radius R_0 . Actually, however, the electrons do deviate somewhat either radially inward or outward from the orbit k and for this reason it is usually necessary to provide some means of stabilization which will return the electrons to the orbit. One practical means of providing the necessary stabilization is to taper the faces of the control poles 13-13' in the direction of the radius as shown in Fig. 1. By so doing, the distribution of the magnetic field at the control poles will then be such as to establish in conjunction with the centrifugal forces stabilizing forces which act on the electrons and form a "potential channel" around the tube, with the orbit k located about midway between the inner and outer boundaries of the channel, and any departure of electrons from the orbit k either radially inward or outward therefrom is counteracted by restoring stabilizing forces of the proper sense existing in the channel.

After the electron stream has been fully accelerated which instant occurs when the magnetic field has reached its maximum value, there arises the problem of removing it from the orbit k in such manner as will assure its travel along a desired path to the point of use. The latter may, for example, be an anti-cathode located in or out of the tube or a reaction chamber located outside of the tube. One method already well known for effecting removal of the electron stream is to establish by electrical fields either electrostatic or electromagnetic in character a deflecting force in a direction perpendicular to a tangent to the orbit k over a small section of the path directly in advance of the desired place of exit. The use of both short deflecting coils or spaced electrodes and which are energized at the proper instant have been proposed for this purpose but it has been found that these expedients are not entirely satisfactory and that the electrons leave the orbit k not at the desired place which is directly behind the deflecting means employed but rather at a point about 180° from the deflecting means and specifically over an undesirably wide angular extent.

In Fig. 3 which has been drawn on the basis of exact calculation of the electron path B, it will be observed that the maximum deviation (ΔR_{max}) of the path B takes place 180° away from the maximum of the curve of the deflecting force F which force is for purposes of explanation assumed to be not so great as would cause the electrons to be shifted radially beyond the boundary within which the stabilizing field acting through the control poles 13-13' is able to guide the electron stream in the direction of the orbital path k notwithstanding the counter action of the deflecting field. Path B also represents the final path of the electrons short of

actual expulsion from the orbit after the force F has had sufficient time to develop its full deflecting effect upon the electrons. As pointed out previously, development of the full effect of the deflection forces requires an extremely long time as compared with the time required by the electrons to make one trip around orbit k and hence transition of the electron stream from orbit k to the final path B as depicted in Fig. 3 will of course be gradual and require several revolutions of the electrons of constantly increasing deflection. In the neighborhood of the point of maximum deviation the curve of the electron path B is comparatively flat with the result that the electrons tend to leave the orbit k over a wide angular extent.

As previously mentioned, I have found that control over the exit or entrance path of the electron stream can be materially improved by setting up additional electrical deflecting forces upon the electrons and which have a radial opposite sense. That is to say, if the first force is directed radially outward, the additional forces will be directed radially inward, and vice versa.

In the construction illustrated in Figs. 1 and 2, the first deflecting force is electrostatic in character and is established by a pair of arcuate electrode plates 22-22' positioned radially inward and outward of the orbit k immediately in advance of the desired place of exit which is the tangentially arranged tube arm 19. As measured in the direction of the path k , the plates 22-22' are quite short and in any event should not extend for more than one fourth of the complete circumference of the path. The additional deflecting force, of opposite sense, is likewise established by a pair of arcuate electrode plates 23-23' positioned radially inward and outward of the orbit k and which are located 180° away from the plates 22-22' as measured along the orbit. The two sets of plates 22-22' and 23-23' are connected in parallel to a source of potential at terminals 24 through a switch 21 and the latter (assuming control over the exit path of the electrons) is arranged to be closed for a brief instant at the end of the acceleration phase by any one of a number of well known control circuits one of which can be found described in my co-pending application, Serial No. 751,680, filed June 2, 1947, now U. S. Patent No. 2,533,859 issued December 12, 1950.

The polarity of the field produced between plates 22-22' will as shown in Fig. 4 be such as to effect a radially inward force upon the electron stream since the exit path is located radially outward from the circular path k , and hence the polarity of the field produced between plates 23-23' must be such as to effect a radially outward force upon the electron stream. This can be taken care of in the connections to the source terminals 24 by connecting the outer plate 22' and inner plate 23 together and similarly connecting together the inner plate 22 and the outer plate 23'.

The beneficial effect of the additional field established by the set of electrode plates 23-23' is quite apparent from an inspection of Fig. 4. In this view, the deflecting force established by the first set of electrode plates 22-22' relative to the orbital path k , here drawn in development, is shown by the curve F_1 , and the additional deflecting force of opposite sense established by the second set of electrode plates 23-23' relative to the path k but 180° removed from plates 22-22' is shown by the curve F_2 . The respective center

maxima of the two curves are of course 180° apart and their combined effect upon the electron path shown by curve B_1 is such as to shift the latter to a position where the maxima ($\Delta R_{1\max}$) of the deviation approximately coincides with the center maxima of the deflecting force established between plates 22-22'. It will be observed that the deviation of the electron path is sharply peaked at the latter location and thus makes it possible to remove substantially all of the electrons at the desired place of exit. In Fig. 4 it will also be understood that for comparison with Fig. 3, the deflecting forces F_1 F_2 are likewise assumed not so great as would cause the electron stream to be deflected beyond the boundary of the orbital channel in which the control field through poles 13-13' is able to redirect the stream in the direction of the orbit k . Hence with such a magnitude of force the electrons would circle continuously around the orbit on path B_1 . Obviously to actually remove the stream radially beyond the stabilizing effect of the control field it is merely necessary to establish larger deflecting forces F_1 F_2 in which case the final electron path would be as indicated by line Z , such path being beyond any possible stabilizing influence of the control field and the electron stream will strike the target anode at X .

The construction shown in Fig. 5 differs from that shown in Figs. 1 and 2 only in that the two sets of deflecting forces are established by the use of coils 25-25' which enclose opposite sides of the control poles 13-13'. However, the effect of the oppositely directed magnetic fields produced by these coils on the electron stream is the same as that produced by the electrostatic fields set up between the sets of electrodes 22-22' and the deflected electron path will be substantially the same as path B_1 of Fig. 4.

If desired, the two sets of oppositely directed deflecting forces may be located adjacent one another as shown in Fig. 6 instead of at opposite sides of the orbital path k . Here the first deflecting force is established electromagnetically by a coil 26, enclosing the control poles 13-13' and located in advance of the exit arm 19 of the tube, and the oppositely directed deflecting force is established by two coils 27-27' also enclosing the control poles 13-13' and which lie adjacent to and on either side of coil 26. As shown in the drawing, coils 27-27' are so interconnected with respect to their common source of power supply that the fields produced by coils 27-27' are both opposite in direction to that produced by coil 26.

Figure 7 illustrates graphically the effect of the deflecting fields produced by coils 26, and 27-27' on the electron path. The force produced by coil 26 is designated F_3 and the forces produced by coils 27-27' are designated F_4 . Here again, it is seen that the maximum deflection ($\Delta R_{2\max}$) of the electron path B_2 from the orbit k coincides with the center of the deflecting force F_3 produced by coil 26 which is the most favorable condition for leading off the electron stream at the desired point of exit.

Figures 8 and 9 illustrate still another possible arrangement of the two sets of deflecting forces. In this form of the invention, the first deflecting force is established by a coil 28 enclosing the control poles 13-13' near the exit arm 19 of the evacuated tube. The oppositely directed force is again divided into two components as in the construction shown in Figs. 6 and 7. However, the coils 29-29' surrounding the control poles 13-13' which produce the oppositely directed

force instead of being located at each side of coil 28 are seen to be arranged unsymmetrically with respect to the latter. That is to say, one of the coils such as coil 29 is located next to coil 28 but the other coil 29' is located approximately 180° away from the other two. Their effect upon the path of the electron stream is illustrated in Fig. 9 where it will be observed that the maximum deviation ($\Delta R_{\max}$) of the electron path B_3 while still located substantially at the position of the deflecting coil 28, its field force being shown by curve F_5 , is quite unsymmetrical to the latter and to the field forces F_6 produced by the other two deflecting coils 29 and 29'.

A modified arrangement is shown in Figs. 10 and 11, it being noted that here the deflecting forces are used for deflecting an electron stream emitted from source 33 into the orbit k for acceleration rather than for guided expulsion of the electron stream after acceleration as in the previously described embodiments. The deflecting forces are derived electrostatically as in Fig. 2 from two sets of electrode plates 34-34' and 35-35' located diametrically opposite one another in the tube 18 at the inner and outer sides of orbit k . Since the two deflecting forces are opposite in direction, i. e. one radially inward and the other radially outward, the inner plate 34 and outer plate 35' are connected together to the same side of potential source 36. Similarly, outer plate 34' and inner plate 35 are connected together to the same but other side of potential source 36. A switch 37 is included in the connections and is adapted to be closed at the instant at which the electron stream is injected into the tube from the electron emissive source 33.

Located between electron source 33 and the pair of electrodes 34-34' are a pair of spaced and charged condenser plates 31-31' through which the electrons pass. As seen in Figs. 10 and 11, electron source 33 and plates 31-31' are located outside of and upwardly from the orbit of acceleration k . The two sets of deflecting plates 34-34' and 35-35' are inclined with respect to the plane of orbit k and the effect of this is to establish by each set a deflecting force having a vector quantity ΔR in the plane of the electron orbit k and another vector quantity ΔV in the plane perpendicular to the plane of the electron orbit.

After the electron stream is emitted from source 33 it follows the path designated B_5 . The electrostatic field produced between the negatively charged condenser plate 31' and the positively charged condenser plate 31 starts the stream radially inward and the deflecting forces set up by the two sets of plates 34-34' and 35-35' will serve to guide the stream radially inward and downward into the plane of the acceleration orbit k . Thereafter the path of the stream will be along orbit k due to the effect of normal magnetic stabilizing forces previously mentioned.

If desired, the arrangement shown in Fig. 11 can be used in reverse to discharge an electron stream from the orbit k at the end of the acceleration phase. In such case the switch 37 would be closed at the instant expulsion of the stream is desired, and the source 33 would be replaced by an anti-cathode, assuming the accelerated electron stream to be used for the production of Roentgen rays. To prevent the accelerated stream from striking the inner condenser plate 31 and being absorbed by the latter, plate 31 is made slightly shorter than the outer plate 31' as shown clearly in Fig. 10.

In Fig. 12, where the plane of the paper corresponds to the plane of the electron orbit there is shown still another arrangement employing oppositely directed deflecting forces on the electron stream for introducing the latter into the potential channel. Here the dimensions of the potential channel are shown in development. Its inner and outer boundaries in the radial direction are indicated by lines 38-38', and the acceleration orbit k lies about midway between the boundaries. An electron source 39 is located just outside of the potential channel and is adapted to shoot a stream of electrons in a direction parallel to, or at a flat angle to, the boundary line 38. The path 40 of the stream is then shifted parallel in the direction of the acceleration orbit k by the field force acting in radial direction and produced by a coil 41 located with its winding parallel to the plane of the electron orbit, the force of the same being indicated by the vector 42. The electron stream after passing coil 41 is then immediately subjected to a force (vector 43) of opposite direction and which is produced by coil 44 located adjacent coil 41 and connected for instance in series with the latter to source terminals 45. The direction of the current flow through the two coils 41, 44 is shown by arrows. The combined action of the two forces 42, 43 on the electron stream is the same as that already described in connection with the preceding embodiments of the invention (especially Figs. 6 and 7), and the electron stream will accordingly be deflected into the potential channel and subsequently reaches the orbit k .

Still another arrangement for setting up the two deflecting forces of opposite direction is illustrated in Figs. 13, 14. Here the first deflecting force is produced by a pair of electrode plates 46-46' extending for a short distance along the circumference of the acceleration path k at the place of electron exit, and the additional deflecting force of opposite sense is produced by a coil 47 enclosing the entire guiding field and producing radial directed forces along the entire electron orbit k . The electron injector is shown at 20 and the anti-cathode at 50. The coil 47 and the deflecting plates 46-46' are connected to the same voltage source 24 and energized by closing the switch 21. The effect upon the electron stream is illustrated in Fig. 14. Here as before, the path k is shown in development, and the deflecting forces due to the coil and the electrode plates are designated respectively by curves F_8 and F_7 . The course of the electron stream is shown by curve B_4 and it will be observed that the latter is shifted radially relative to the orbit k when compared with the curve shown in Fig. 3, so that the point of maximum deflection ($\Delta R_{\max}$) from the orbit k occurs at the location of electrode plates 46-46', i. e. at force F_7 .

The arrangement shown in Fig. 13 serves the purpose of modifying the normal ratio between the control and induction field components produced by coils 16-16', and thus produce the already described second force acting in an opposite sense and simultaneously with the first named deflecting force upon the electrons. This alteration of the ratio between the control and induction field components can also be established in some other well known manner, such as by effecting a saturation of the induction poles 11-11' or the control poles 13-13' at the proper instant, or by causing a phase displacement between the control and induction field components. The means required to produce

the saturation of the induction poles or the control poles are well known and are described in detail for instance in U. S. Patent No. 2,103,303. Similarly the phase displacement referred to above can be achieved by well known means such as described in the U. S. Patent No. 2,297,305.

In conclusion, I wish it to be understood that while the various constructional arrangements have been illustrated as applied to an electron accelerator of the betatron type, the principles of the invention are equally applicable to other types of electron devices where the electrons describe circular paths such as for example in the synchrotron and beta ray spectographs.

I claim:

1. In an electron device such as an electron accelerator and the like wherein the electrons travel along a circular orbit, means for effecting a deflection of the electrons at a preselected point along said orbit comprising, means establishing a first deflecting field immediately in advance of said point of deflection, said field extending along said orbit for at most one-fourth the circumference thereof and which produces a generally radial deflecting force upon the electrons, and means simultaneously establishing a second deflecting field elsewhere along said orbit and which also produces a generally radial deflecting force upon the electrons but which force is of opposite sense to the force produced by said first field.

2. An electron device as defined in claim 1 wherein the respective means producing said first and second fields are so oriented with respect to said orbit as to yield a component of deflecting force perpendicular to the plane through said orbit.

3. An electron device as defined in claim 1 wherein the means establishing said second field extends substantially over the circumference of said orbit.

4. An electron device as defined in claim 1 wherein at least one of said field producing means is located in such position that the deflecting force produced thereby is effective in the radial direction over only a portion of the width of the potential channel containing said orbit.

5. An electron device as defined in claim 1 wherein the respective means for producing said first and second deflecting forces are comprised of coils surrounding at least parts of said orbit.

6. An electron device as defined in claim 1 wherein the respective means for producing said first and second fields are comprised of pairs of electrodes located radially inward and outward of said orbit.
7. An electron device as defined in claim 1 wherein the said respective means establishing said first and second fields are disposed adjacent one another.
- 10 8. In a device for accelerating electrons comprising an annular tube within which a stream of electrons following a circular orbit may be accelerated to high velocity, a magnetic field structure associated with said tube and which includes a central induction pole surrounded by said tube and a pair of annular control poles in juxtaposed relation of said orbit, and a winding surrounding said induction and control poles adapted to be energized with alternating current to establishing magnetic fields varying with time in said induction and control poles and under the influence of which said stream of electrons is accelerated; means for effecting a deflection of the electron stream at a preselected point 15 along said orbit, said deflecting means comprising means establishing an electrical field immediately in advance of said point of deflection, said field extending along said orbit for at most one-fourth the circumference thereof and which 20 produces a first and generally radially acting deflecting force upon the electron stream, and means for changing the magnitude of the control field in said control poles relative to the magnitude of the magnetic field in said induction poles thereby establishing a second deflecting force on said electrons acting in a radial opposite sense to and simultaneously with said first 25 deflecting force.
